FULL LAMINATED RELAY

Bertil S. Bengtsson, Plantsville, Conn., assignor to The Five Star Company, Inc., Plantsville, Conn., a corporation of Connecticut

Application June 2, 1954, Serial No. 434,012

12 Claims. (Cl. 200—111)

This invention relates to relays and is directed particularly to an improved relay construction providing greater efficiency and reliability, especially in A. C. relays.

The efficiency of an A. C. relay depends to a great extent upon how completely the magnetic circuit is laminated. A. C. relays are ordinarily so constructed that they have only a partially laminated magnetic circuit—solid magnetic armatures usually being provided as the actuating mechanism for the moving contacts. Not only are such relays inefficient, but they are also faulty in operation when subjected to shock and vibration due to the great weight and consequent inertia of such movable magnetic armatures.

It is accordingly an object of this invention to provide an improved relay having a complete laminated magnetic structure including a light weight moving plunger.

It is another object of the invention to provide a relay of the above nature having parallel side extensions in the central leg portion of the laminated magnetic circuit, which extensions serve to reduce the required size and weight of the plunger, to reduce the reluctance of the magnetic circuit, and also serve as a guide means for the plunger.

A further object of the invention is to provide an A. C. relay of the above nature having a construction incorporating a shading coil of large cross section without loss of pole face area.

Still another object of the invention is to provide a relay of the character described in which the usual current-carrying springs connected to moving contacts are eliminated, and wherein leaf springs of thin flat stock having a flat characteristic are utilized, thereby reducing the magnetic force necessary to overcome plunger chatter in A. C. relays when the plunger is in actuated or closed position.

Still further objects and advantages of the present invention will appear from the more detailed description set forth below, it being understood that this description is given by way of illustration only, and that various changes therein may be made by those skilled in the art without departing from the spirit and scope of the appended claims.

In the drawings, wherein like reference numerals denote corresponding parts throughout the several views:

Fig. 1 is a side elevational view of a four pole double throw A. C. relay embodying the invention,

Fig. 2 is a top view of the relay shown in Fig. 1,

Fig. 3 is an end view of the same,

Fig. 4 is a longitudinal vertical cross section of the same, taken on the line 4—4 of Fig. 2,

Fig. 5 is a transverse vertical cross section of the same, taken on the line 5—5 of Fig. 2, and

Fig. 6 is a transverse vertical cross section, taken along the line 6—6 of Fig. 2.

In the drawings, the numeral 10 indicates generally a four pole double throw A. C. relay embodying the invention. In brief, the relay comprises a pair of spaced mounting brackets 11, 12 between which is secured a

2

laminated magnetic core 13 having a central leg portion within which is disposed for vertical movement a laminated plunger 14 of magnetic material.

Surrounding the central leg portion of the core 13 is an insulated electric winding 15 for energizing the relay. The plunger 14 carries in its slotted upper end a pair of face-to-face contact links 16, 17 of light insulation material, and said links extend outwardly of the core 13 equidistantly in each direction (see Fig. 4).

The contact links 16, 17 have resiliently supported therein transversely disposed contact members 18, 19, 20 and 21, said contact members being adapted to shunt, selectively, horizontally aligned upper or lower contacts of the contact pair 22, 23 fixed in position between partitions of electrical insulating material secured against either side of the laminated core 13 by means of left- and right-hand end support plates 24, 25. Contact return leaf springs 26 secured between the partitions serve to urge the contact links 16, 17 upwardly so that the plunger 14 is in withdrawn position in the magnetic circuit, and so that the transversely aligned contacts 22 are normally electrically interconnected. Upon energization of the electric winding 15, the plunger 14 will be pulled downwardly, carrying with it the four contact members 18, 19, 20 and 21 so that cross contact is then made between the transversely aligned lower contacts 23.

Considering now the detailed construction of the relay 10, it will be evident that, as best illustrated in Fig. 6, the laminated core 13 comprises a pair of opposed downwardly-extending portions 27, 28 defining a vertical slot 29 within which the laminated plunger 14 is guided.

The core 13 has a V-shaped recess 30 below the downwardly-extending portions 27, 28, said recess being adapted to receive the correspondingly-shaped integral enlarged head 31 at the lower end of the plunger 14. The core 13 is provided with a pair of parallel vertical slots 32 within the V-shaped recess 30, said slots extending cross-wise through the core laminations and being adapted to receive and support a centrally-apertured saddle-shaped shading coil 33. Such a shading coil is not necessary, of course, if the relay is to be energized for actuation only by direct current.

The energizing magnet winding 15 is wound on a substantially square paper insulation tube 34 and then hermetically sealed by molding it in a suitable plastic insulating covering 35.

In assembling the laminated core 13, the laminations thereof are inserted individually within the winding 15, the plunger 14 will have been first inserted, and thereafter riveted together between the centrally-apertured mounting brackets 11, 12 by means of four corner rivets 36, as is best illustrated in Figs. 1, 5 and 6.

A pair of shallow U-shaped plunger guide members 37, 38 preferably of some non-magnetic material such as brass, are fitted at each side within the square central opening in the winding 15, serving to guide the enlarged plunger head 31 in its vertical path of travel.

The plunger 14 is prefabricated with its laminations secured together by 3 headed pins 39. The plunger 14 is provided with an elongated rectangular slot 40 near the upper end thereof, said slot being furnished to support the contact links 16 resiliently, in a manner hereinbelow more fully described (see Figs. 4 and 6).

The contact links 16 and 17 are identical, each having a generally rectangular recess 41 within which the upper end of the plunger seats when said links are assembled in the rectangular opening 40 thereof. The bottoms of the recesses 41 of the links 16, 17 are shaped to provide a pair of oppositely inclined surfaces, indicated by the numerals 42, 43, respectively (see Fig. 4), and said links

are assembled in reversed end-to-end position, whereby the inclinations extend in opposite directions. Arcuate recesses 44, centrally disposed along the lower edge of the contact links 16, 17 are provided to receive the upper end of a horizontal contact link index coil spring 45 when the contact links are in assembled position in the plunger 14. Thus, by virtue of the oppositely-extending inclined surfaces 42, 43 and the index spring 45, the contact links 16, 17 are rockably held with respect to the plunger 14.

The contact members 18, 19, 20 and 21 also are resiliently supported in generally rectangular openings 46, 46a in the contact links 16, 17 and extend equidistantly from either side thereof (Fig. 4). The openings 46a are made slightly deeper than the openings 46 to provide self-alignment of said contacts in unenergized position and to allow for wear of said contacts.

The openings 46 each have aligned opposed slots 47 through which, during assembly, the contact members 18, 19, 20, 21 and the flanged contact spring seats 48 can be passed. The flange portions of the contact spring seats 48 have diametrically opposed cut-out portions enabling said seats to be secured against the upper edges of the openings 46. The contact members 18, 19, 20 and 21 are similarly provided with opposed generally rectangular recesses 49, whereby they can be assembled through the slots 47 and seated down against the lower edges of the openings 46. The contact members 18 through 21 have central upwardly-protruding portions 50, provided for instance by the use of round studs secured in said contact members, for indexing contact springs 51 disposed within the openings 46 between the contact spring seats 48 and said contact members.

It will thus be apparent that when the relay is energized, normal downward over-travel of the plunger 14, whereby the contact members 18, 19, 20, 21 will be moved downward into contact with their respective contact pairs 23 before said plunger is in fully retracted position, results in compression of the contact springs 51, thereby insuring uniform contact pressure between the contacts.

The contact pairs, as hereinabove described, are secured between partitions of electrical insulating material. To support these partitions, the mounting brackets 11 and 12 each have fixed thereto four outwardly-extending studs 52. Since the construction is the same at both sides of the relay, only the right-hand side, as illustrated, will be described herein.

Mounted against the outside of the mounting bracket 11 and 12 are a pair of inverted L-shaped insulators 53, it being understood that said insulators, as well as all the other insulators hereinbelow described, are apertured to allow passage therethrough of the studs 52. A pair of slotted L-shaped spacer insulators 54 are mounted against the insulators 53. Four cylindrical spacer horizontal insulators 55 are mounted on the four studs 52 against the spacer insulators 54, followed by a second pair of slotted spacer insulators 56, a second pair of insulators 57, a third pair of slotted spacer insulators 58, a second set of cylindrical spacer insulators 59, a fourth pair of slotted spacer insulators 60, a third pair of insulators 61 and finally the left-end support plate 25. The assembly is securely held together by swedging over the outer ends of the studs 52.

Aligned elongated slots are provided in the slotted spacer insulator pairs for securing in position the contact pairs 22, 23 between the partitions, said contact pairs having corresponding side projections fitting into said slots. The L-shaped insulators are so disposed as to define aligned vertical central slots which together with a vertical slot 25a in the end support plate 25, allow unobstructed vertical motion of the contact links 16, 17.

In order to resiliently hold the plunger 14 upwardly in normal (not energized) position, so that the contact members 18, 19, 20 and 21 make contact with their respective contact pairs 22, 23, the flat angularly bent con-

tact return springs 26, preferably of beryllium-copper, are located, one within each of the partition spaces. The leaf springs 26 (see Fig. 5) each have a downwardly-extending portion 62 fitting over the outer surfaces of the respective vertically-aligned pairs of the cylindrical spacer insulators 55 and 59, and an inwardly-extending portion 63 the end of which bears upwardly against the contact links 16, 17 within shallow locating slots 64, 64a therein (see Fig. 5). The slots 64a are deeper than the slots 64 for permitting self-alignment of the contacts and to allow for wear. The return springs 26 are adjustably held in place by means of side screws 65 passing through a central aperture in the downwardly extending portion 62 thereof and into respective nuts 66 mounted between the slotted spacer elements in the same way as are the contact pairs 22, 23 described above.

For convenience in making connection to the magnetic winding 15, the electrical leads 67 are connected to terminal connector members 68, one at each side of the relay in the first partition space, opposite the contact return springs 26. The terminal connector members 68 are also secured in slots of the spacer insulators 54, 56 and have an outwardly-extending lug 69 for connection of the relay energization circuit.

One of the advantages of the novel relay herein disclosed is that contact is made without the use of current-carrying springs, thereby increasing the current carrying capacity.

Another advantage resides in the novel contact return spring construction wherein adjustment can be made without bending of spring-tempered parts.

Another advantage resides in the flat characteristic of the return springs, which minimizes the magnetic pull required for maintaining the plunger in actuated position, thereby eliminating plunger chatter in A. C. relays.

Another advantage resides in the efficiency of the magnetic circuit, combined with great reduction in weight in the plunger and the contact carrying parts, whereby the resistance of the relay to shock and vibration is increased.

While there has been described and illustrated herein one embodiment of the invention, it is to be understood that this embodiment is presented as an example only and that various changes and modifications will occur to those skilled in the art without departing from the spirit and scope of the invention as defined in the following claims.

Having thus fully described the invention what is claimed as new and for which it is desired to secure Letters Patent, is:

1. In an electromagnetic relay, the combination comprising, a substantially rectangular laminated magnetic core having a central opening, said magnetic core comprising spaced opposed magnetic core portions extending into said central opening and defining a slot in said core, a laminated armature plunger member of magnetic material in said slot, said plunger comprising at one end an integral enlarged head located within said opening and below the ends of said opposed magnetic core portions, said plunger being movable longitudinally within said slot, an electric winding adapted to induce a magnetic flux in said core, an elongated contact carrying insulating structure, means rockably mounting said structure to the other end of said plunger member, and resilient means cooperative with said structure for holding said plunger member so that it is in withdrawn position relative said core when the coil is not energized.

2. The invention as defined in claim 1, wherein said winding surrounds said opposed magnetic core portions and said plunger.

3. The invention as defined in claim 1, wherein said structure mounting means comprises a slot in said plunger member, said structure being located in said plunger slot, and a coil spring in said slot between said structure and an inner surface of said slot.

4. The invention as defined in claim 3, wherein said spring is disposed edgewise relative to said structure, and

wherein said structure is provided with an arcuate recess for receiving the edge of said spring.

5. The invention as defined in claim 3, wherein said structure comprises a pair of flat face-to-face elements, each element having a cut-out portion defining an inclined bottom surface, said elements being relatively so disposed that the inclined surfaces extend in different directions.

6. The invention as defined in claim 1, wherein said enlarged head is of V-shaped formation, and wherein said core is provided with a corresponding V-shaped recess adapted to receive said V-shaped head therein.

7. The invention as defined in claim 6, wherein the V-shaped recess of said core is slotted in each side across the laminations, and including a saddle-shaped centrally 15 apertured shading coil having downwardly-extending side portions seated in said slots.

8. The invention as defined in claim 1, wherein said resilient plunger-holding means comprises a flat spring having one end adapted to engage with the underside of 20 said structure.

9. The invention as defined in claim 8, including a pair of spaced spring support members, the other end of said spring being bent over said members, and adjustable pressure means for holding the central portion of the other end of said spring so that said other end is in firm engagement with said spring support members, whereby the compressional force of the other end of said spring upon the underside of said structure can be varied.

10. The invention as defined in claim 1, wherein said 30

contact carrying structure extends substantially equidistantly from each side of said plunger member, a plurality of double contact shunt members crosswise and resiliently mounted in said structure, and pairs of spaced contacts cooperatively mounted with respect to each contact of each of said double-contact shunt members so that when said relay is energized, said shunt members each switch from one set to the other of individual contacts of said pairs of spaced contacts.

11. The invention as defined in claim 1, wherein said structure has two pairs of rectangular openings for loosely receiving said contacts, the openings of one pair being deeper than the opening of the other pair to provide self-alignment of said contacts in the unenergized position of said plunger and to allow for wear.

12. The invention as defined in claim 8, in which the underside of said structure has two pairs of spring-receiving notches, one pair of said notches being deeper than the other pair to provide self-alignment of said contacts in the unenergized position of said plunger and to allow for wear.
